D12-20. OR D 13,390 EX

No. 13,390

Oct 31, 1882

UNITED STATES PATENT OFFICE.

JOHN L. POPE, OF CLEVELAND, OHIO.

DESIGN FOR A WHIFFLETREE-PLATE.

SPECIFICATION forming part of Design No. 13,390, dated October 31, 1882.

Application filed August 2, 1882. Term of patent 7 years.

To all whom it may concern:

Be it known that I, JOHN L. POPE, of Cleveland, in the county of Cuyahoga and State of Ohio, have invented and produced a new and original Design for Whiffletree-Plates, of which the following is a specification, reference being had to the accompanying engraving, forming part thereof.

My invention relates to a new design for whiffletree-plates; and it consists in the shown configuration thereof.

In the accompanying engraving, A and B represent two whiffletree-plates similar in make and design, with the exception that the plate 15 A is made with a round hole, while the plate B is made with a square hole or opening to receive the square neck of a bolt and prevent its turning in the plate, as well understood by those skilled in the art to which my invention

appertains. At the extremities of the plates 20 are countersunk holes *a* for attachment by screws of the plates to the whiffletrees, and at about the middle of each plate is a raised portion, *b*, round in figure and tapering, as shown. The edges of each plate curve inwardly from 25 the raised portions *b*, at either side thereof, until at about a point opposite the screw-holes *a*, when they curve outwardly and meet in a point, *c*.

What I claim as new, and desire to secure by 30 Letters Patent, is—

The shown design for whiffletree-plates.
In witness whereof I hereunto set my hand
this 22d day of June, 1882.

JOHN L. POPE.

In presence of—
C. M. COPP,
CHAS. W. MOSES.
